RAISING AND LOWERING MEANS IN METAL-WORKING MACHINERY.

1,380,021.

Specification of Letters Patent. Patented May 31, 1921.

Application filed September 10, 1917. Serial No. 190,657.

To all whom it may concern:

Be it known that we, ALBERT E. ROBINSON and HERMAN W. SCHATZ, citizens of the United States, residing, respectively, at Cincinnati, and at Norwood, in the county of Hamilton and State of Ohio, have jointly invented certain new and useful Improvements in Raising and Lowering Means in Metal-Working Machinery, of which the following is a specification.

Our invention relates to means for raising and lowering a substantially heavy part of a metal working machine on a support or column, and it has for its object the provision of novel means whereby breakage, due to carelessness or abnormal loads, is avoided.

We have exemplified our invention as employed in a so-called drilling machine, for raising and lowering the drill-arm on the column. The means for effecting such raising and lowering, or adjustment of the arm to elevation on the column, is exemplified as a screw-rod which has threaded engagement with the arm, and is arranged to be rotated in reverse direction by means of gearing. The arm is arranged to be fixed to the column in its adjusted positions. When so clamped, the arm is rigid with the column. If now an attempt should be made under usual structures as heretofore made, to raise or to lower the arm while the same is clamped to the column, the operating parts would be subjected to excessive stress with the practical certitude of breakage of parts or stripping of gears.

It is the object of our invention to avoid these objections, and to provide means which perform their power transmitting function under normal loads and yield to abnormal loads; further to provide yielding pressure means for such means; and, further, to provide means for adjusting the pressure.

It is a further object of our invention to provide novel means for absorbing shocks or sudden stresses in the raising and lowering mechanism of the character mentioned, as when the direction of movement of the raising and lowering mechanism is reversed, or the power thereof suddenly applied for effecting a change of elevation of the supported part.

The invention will be further readily understood from the following description

and claims, and from the drawings, in which latter:

Figure 1 is a front elevation of a drilling machine embodying our invention, and partly broken away.

Fig. 2 is a rear elevation of the same.

Fig. 3 is a plan view of our improved device applied in a drilling machine, the latter partly broken away, and the top gear-cover removed.

Fig. 4 is a vertical section of the same, taken in the plane of the line 4-4 of Fig. 3.

Fig. 5 is a vertical section of the same, taken in the plane of the line 5-5 of Fig. 3.

The drilling machine, exemplified as embodying our invention, is shown as a radial drilling machine, including a base 11, from which a post 12 extends upwardly, the post having a column 13, shown as a rotatable cylindrical column, received thereabout, the column being supported and rotatable in any ordinary or well-known manner, and arranged to be clamped in adjusted positions to the post or base by means of a usual clamp 14. The column may represent any suitable support. An arm 15 is adjustable to elevation on the column and has a bearing 16 about the column. The arm may represent any suitable bracket. When in adjusted position, the bearing is arranged to be clamped in fixed relation to the column by usual clamps 17.

A drill-head 18 is adjustable laterally on the arm, as by means of a hand-wheel 19, which operates a suitable pinion meshing with a rack 20 extending lengthwise of the arm, the drill-head being slidable laterally on the arm on guideways 21. The drill-head has a suitable drill-spindle 22 rotatably driven and axially feedable on the drill-head. It may have a suitable tool, as a drill 23 fixed therein, the primary object of the adjustment of the drill-arm on the column, in the present exemplification, being to adjust the arm for proper working relation of the drill to the work, exemplified at 24 as a metal casting located on or secured to the table 25.

The drill may be operated by means of a shaft 31 extending lengthwise of the drill-arm, having usual operative connection with the drill-spindle for rotatively driving and for feeding the same. The shaft 31 has a

bevel-gear 32 fixed thereon, which meshes with the bevel-gear 33 rotatable in and held axially to a bearing 34 on the drill-arm, an upright shaft 35 having spline-connection 36 with said bevel-gear 33.

The upright shaft is journaled in a bearing 37 in the column and a bearing 38 in a cap and gear-housing 39 fixed to the upper end of the column, as by set-bolts 40. A gear 41 is fixed to the upper end of the upright shaft and meshes with a gear 42, which rotates with a gear 43, the gears 42, 43, being keyed together by a key 44. The gears 42, 43, rotate on a stud-shaft 45 fixed in a bearing 46 of the gear-housing, as by a set-bolt 47. The gear 42 meshes with a gear 48, fixed to the upper end of a shaft 49, journaled in a bearing 50 in the gear-housing and in suitable bearings in the post 12, and having a bevel-gear 51 at its lower end, which is meshed by a bevel-gear 52, on a power shaft 53, arranged to be rotated at selective speeds, as by means of a step-pulley 54.

The means for adjusting the arm to elevation on the column are exemplified as a screw-rod 61, which has threaded engagement with the arm, as by means of a nut 62, received in a recess 63 in the arm, the arm finding support on the nut by means of an annular ledge 64 of the arm, the nut being fixed non-rotatively to the arm by means of a set-bolt 65. The lower end of the screw-rod may be journaled in a bearing 66 on the column. The upper end of the screw-rod is received through a bushing 71, located in a bearing 72 of the gear-housing 39. The bushing has a shoulder 73, whereby it has support on the bearing, and an enlarged journal-part 75. A collar 77 is received about the screw-rod, being pinned thereto by a pin 78, the collar bearing against the lower end of the bearing 72. A supporting bearing 81 is provided for the screw-rod above the bushing 71, this supporting bearing being exemplified as a ball-bearing, an end-thrust collar 82 resting on the ball-bearing and having threaded engagement 83 with the screw-rod. The end-thrust bearing may be pinned to the screw-rod by a pin 84.

Collars 86, 87, are received about the screw-rod, the axes of rotation of the collars being coincident with the axis of rotation of the screw-rod. The collars are rotatively fixed to the screw-rod, as by having spline-connection 88 therewith. Relative axial movement is permitted between the collars. The respective collars have friction-flanges 91, 92. A gear 93 is provided with an inner friction flange 94 received between the friction-flanges 91, 92. The gear has a central bore 95, the wall of which bears on the annular hubs 96 of said collars 86, 87. Friction washers 97, 98, are

received between the friction-flange on the gear and the friction-flanges on the respective collars. The washers are axially positioned with relation to the flanges by being provided with central bores 99 in which 70 said hubs are received.

The gear 93 meshes with a gear 101 journaled on a stud-shaft 102 secured in a bearing 103 of an arm 104 of a rocking lever 105. A gear 106 is fixed to the upright 75 shaft 49 and in the present exemplification rotates with the gear 48. The gears 43, 106, rotate in opposite directions, effected by rotation of the gear 106 by the shaft 49, the rotation of the gear 48 with gear 80 106, the meshing of the gear 48 with the gear 42, and the rotation of the gear 43 with the gear 42.

The gears 43, 106, 42, and 43, normally rotate. The gear 101 is normally out of 85 mesh with both the gears 43 and 106. When brought into meshing relation with one of said gears, the gear 101 is rotated in one direction, for rotating the screw-rod in a given direction, and lowering the arm on 90 the column. When the gear 101 is caused to mesh with the other of said gears, the gear 101 is rotated in the opposite direction, the screw-rod being oppositely rotated, and the arm raised on the column. 95

It is necessary to unclamp the bearing of the arm about the column prior to the raising or lowering of the arm. Sometimes, due to carelessness, the operator attempts to raise or to lower the arm without unclamping the bearing. In case this is done 100 breakage of parts or stripping of gears in my improved device is prevented, by the fact that the gear 106 is permitted to yield with relation to the screw-rod through the 105 medium of the friction devices coacting therewith.

The rocking lever 105 comprises the arm 104, to which the stud-shaft 102 is secured for carrying the gear 101, and an arm 111 110 which is an operating arm. The rocking lever has a bearing 112 about the enlargement 75 of the bushing 71. The rocking lever is operated by means of a rocker-rod 115, journaled at its lower end in a bearing 116 of the column, and at its upper end in a bearing 117 in the gear-housing 39. The rocker-rod is provided with a handle 118 extending radially therefrom for rocking the rod. A segment-gear 121 is secured to 120 the rocker-rod at its upper end, this segment-gear meshing with a segment-gear 122 on the operating arm of the rocking lever.

In order to effect rocking movement of the rocking lever to proper extent to obtain 125 proper meshing relation between the gear 101 and the respective gears 43 and 106, means are provided for limiting the rocking movement of the rocker-rod, accomplished by providing the segment-gear 121 with lugs 130

123, through which set-bolts 124 extend, acting as stops, the set-bolts being adjustable in said lugs and clamped in adjusted positions by means of jam-nuts 125. The projecting ends of the set-bolts coact with faces 126, acting as stops, to determine the limits of rocking movement of the rocking lever. Resilient means are preferably provided for determining the frictional resistance of 10 the friction elements, exemplified as a spring 131 exerting pressure on the friction elements, the spring being received about an upper threaded end 132 of the screw-rod and in an annular recess 133 of a nut 134 threaded to said threaded end for adjusting the tension of the spring. A jam-bolt 135 is received in the threaded bore of the nut and is arranged to impinge the upper end of the screw-rod for locking the nut in adjusted position. The nut and jam-bolt are received through an aperture 136 in the gear-cover 137, so that the same may be adjusted from the outside of the machine.

By means of our improved device a resilient pressure is applied to the friction elements, for causing the same to act under normal pressures or loads, and preventing an undesirable slippage between the friction elements, and insuring the coaction of 30 the friction elements during normal loads. The degree of resistance of the friction elements is adjusted by means of the adjustment of the spring, so that the resistance under which the friction elements shall yield, may be adjusted in accordance with the load it is desired that the friction elements shall move.

The spring further aids the friction elements in acting as a cushion in the power 40 transmission to the screw-rod, and in absorbing the shocks incident to initiating movement in the screw-rod, and occasioned by reversals of rotation thereof, and compensates for sudden stresses therein.

45 If now an attempt be made to raise or lower the arm during clamped relation of the bearing thereof about the column, the friction elements will yield so as to prevent injury of the parts or stripping of 50 teeth of the gears. If, furthermore, the attempt be made to impart sudden rotation to the screw-rod, for instance in raising the arm, resulting in stress upon the parts or the teeth of the gears in excess of the load 55 contemplated for the same, the friction elements will yield until the resistance thereof overcomes the inertia of rest of the load and initiates the movement of the load without shock.

60 Having thus fully described our invention, what we claim as new and desire to secure by Letters Patent, is:

1. In a metal working machine, the combination of a support, a part adjustable to 65 elevation thereon, and means for adjusting

said part to elevation comprising friction transmitting means arranged to transmit normal loads and to yield to abnormal loads, and means for supporting said part independent of the friction contact of said friction transmitting means during adjustments of said part. 70

2. In a metal working machine, the combination of a support, a part adjustable to elevation thereon, means for adjusting said 75 part to elevation comprising friction transmitting means arranged to transmit under normal loads and to yield to abnormal loads, means for supporting said part, during adjustments of said part, independent of the 80 friction contact of said friction transmitting means, and means for adjusting the transmitting effect of said friction transmitting means.

3. In a metal working machine, the combination of a support, a part adjustable to elevation thereon, means for adjusting said 85 part to elevation comprising a friction transmitting means arranged to transmit under normal loads and to yield to abnormal loads, means for supporting said part independent of the friction contact in said friction transmitting means during adjustments of said part, and yielding pressure means for cushioning said friction transmitting means. 90

4. In a metal working machine, the combination of a column, an arm, means for raising and lowering said arm on said column comprising a nut non-rotatively fixed 100 to said arm, an upright screw axially held and rotative with relation to said column, a driving member, said screw constituting a driven member, a power transmitting friction member between said driving member and said driven member arranged to yield to abnormal load and to cause driving relation between said driving member and said driven member under normal load, and resilient means acting on said power transmitting friction member to cushion said raising and lowering means. 110

5. In a metal working machine, the combination of a column, an arm, means for raising and lowering said arm on said column comprising a nut non-rotatively fixed 115 to said arm, an upright screw axially held and rotative with relation to said column, a driving member, said screw constituting a driven member, a power transmitting friction member between said driving member and said driven member arranged to yield to abnormal load and to cause driving relation between said driving member and said driven member under normal load, resilient 120 means acting on said power transmitting friction member to cushion said raising and lowering means, and means for adjusting said resilient means. 125

6. In a metal working machine, the com- 130

bination of a column, an arm adjustable to elevation thereon, means for clamping said arm to said column in adjusted positions and means for adjusting said arm to elevation on said column comprising friction means including a driving member, a driven member and a friction member therebetween, and a coacting screw and nut having elevating and lowering effect on said 5 arm, said coacting screw and nut supporting said arm against gravity independent of the friction contact in said friction means, arranged to yield during clamped relation of said arm on said column and to 10 adjust said arm on said column during unclamped relation of said arm.

7. In a metal working machine, the combination of a column, an arm adjustable to elevation thereon, an upright screw-rod extending lengthwise of said column having threaded engagement with said arm for raising and lowering the same, a supporting bearing for said screw-rod, an end-thrust collar fixed to said screw-rod and supported 20 by said supporting bearing, means for rotating said screw-rod comprising a gear whose axis of rotation is coincident with the axis of rotation of said screw-rod, a collar rotatable with said screw-rod, and 25 friction means between said gear and collar arranged to rotate said screw-rod under normal loads on said screw-rod and to yield to abnormal loads on said screw-rod, said end-thrust bearing supporting said screw-rod independent of the friction contact in 30 said friction means.

8. In a metal working machine, the combination of a column, an arm adjustable to elevation thereon, an upright screw-rod 40 extending lengthwise of said column having threaded engagement with said arm for raising and lowering the same, a supporting bearing for said screw-rod, an end-thrust collar fixed to said screw-rod and supported by said supporting bearing, means for rotating said screw-rod comprising a gear whose axis of rotation is coincident with the axis of rotation of said screw-rod, a collar rotatable with said screw-rod, and 45 friction means between said gear and collar arranged to rotate said screw-rod under normal loads on said screw-rod and to yield to abnormal loads on said screw-rod, and means for adjusting the friction resistance between said gear and collar, said end-thrust bearing supporting said screw-rod independent of the friction contact in 50 said friction means.

9. In a metal working machine, the combination of a column, an arm adjustable to elevation thereon, an upright screw-rod extending lengthwise of said column having threaded engagement with said arm for raising and lowering the same, a supporting 60 bearing for said screw-rod, an end-thrust

collar fixed to said screw-rod and supported by said supporting bearing, means for rotating said screw-rod comprising a gear whose axis of rotation is coincident with the axis of rotation of said screw-rod, a collar 70 rotatable with said screw-rod, means between said gear and collar arranged to rotate said screw-rod under normal loads on said screw-rod and to yield to abnormal loads on said screw-rod, and means comprising a spring acting yieldingly on said friction means for cushioning said friction means, said end-thrust bearing supporting said screw-rod independent of the friction contact in said friction means. 75

10. In a metal working machine, the combination of a column, an arm adjustable to elevation thereon, an upright screw-rod extending lengthwise of said column having threaded engagement with said arm for adjusting said arm to elevation on said column, a supporting bearing in which said screw-rod is journaled, an end-thrust collar fixed to said screw-rod and supported by said supporting bearing, a gear about said screw-rod whose axis of rotation is coincident with the axis of rotation of said screw-rod, opposed collars arranged to rotate with said screw-rod and having relative movement between them axially of said screw-rod, said 90 gear provided with an annular flange received between said collars, friction washers between said flange and each of said collars, and resilient means causing coaction between said flange, said collars and said friction washers, and said end-thrust collar supporting said screw-rod independent of the friction contact in 95 said friction means.

11. In a metal working machine, the combination of a column, an arm adjustable to 105 elevation thereon, an upright screw-rod extending lengthwise of said column having threaded engagement with said arm for adjusting said arm to elevation on said column, a supporting bearing in which said screw-rod is journaled, an end-thrust collar fixed to said screw-rod and supported by said supporting bearing, a gear about said screw-rod whose axis of rotation is coincident with the axis of rotation of said screw-rod, opposed collars arranged to rotate with said screw-rod and having relative movement 110 between them axially of said screw-rod, said gear provided with an annular flange received between said collars, friction washers between said flange and each of said collars, resilient means causing coaction between 115 said flange, said collars and said friction washers, means for adjusting the pressure of said resilient means, and said end-thrust bearing supporting said screw-rod independent of the friction contact in 120 said friction means.

12. In a metal working machine, the combination of a column, an arm adjustable to 125

elevation thereon, means for clamping said arm to said column, an upright rotatable screw-rod having threaded connection with said arm for raising and lowering said arm 5 on said column, a bearing for said screw-rod for supporting said screw-rod in the direction of its axis, an end-thrust collar fixed to said screw-rod and supported by said supporting bearing, opposed collars rotatable with 10 said screw-rod and having axial movement between them, a gear provided with an inner annular flange received between said collars and having an axis of rotation coincident with the axis of rotation of said screw-rod, friction-members between said flange and each of said collars, means for exerting 15 yielding pressure on said friction-members, means for rotating said gear in reverse di-

rections, said gear arranged to rotate said screw-rod through the medium of said friction-members during unclamped relation of 20 said arm, and said friction-members permitting rotation of said gear with relation to said screw-rod during clamped relation of said arm to said column, and said end-thrust bearing supporting said screw-rod independent 25 of the friction contact in said friction means.

In testimony whereof, we have hereunto signed our names in the presence of two sub- 30 scribing witnesses.
